UNITED STATES PATENT OFFICE.

EDWARD B. HESS, OF MANHATTAN BEACH, NEW YORK, ASSIGNOR TO ROYAL TYPE-
WRITER COMPANY, INC., OF NEW YORK, N. Y., A CORPORATION OF NEW YORK.

TYPEWRITING MACHINE.

Application filed November 17, 1921. Serial No. 515,842.

To all whom it may concern:

Be it known that I, EDWARD B. HESS, a citizen of the United States, residing at Manhattan Beach, county of Kings, New York, and State of New York, have invented certain new and useful Improvements in Typewriting Machines, of which the following is a specification.

This invention relates to typewriting machines of the front-strike visible class in which the type bars are pivotally connected with a vertically arranged segment and normally lie horizontally, being link-connected with key levers arranged in stepped banks or rows below the plane of the type bars.

One of the principal objects of my invention is to provide means whereby the noise produced by the impact of the type bars on the platen may be reduced. In my United States Patent No. 1,390,708, of September 13, 1921, I have shown means whereby such noise may be greatly reduced by so organizing the mechanism that when the key levers are depressed the type bars are moved to a position considerably in advance of the platen, the further movement of the type bars to the platen being caused by their momentum, and therefore such subject matter is not broadly claimed herein.

According to my present invention a direct connection is made by means of links between the type bars and the key levers, the key levers being provided with upwardly projecting arms between their opposite ends and the arm of each lever being connected by a single link to the heel of an associated type bar. In this organization, when a key is depressed the associated type bar is moved to a predetermined position in front of the platen and the type bar is further moved by its momentum to the printing point. In this way the noise of impact is reduced.

The escapement mechanism is operated, during the momentum period of the type bars, by a universal bar mechanism of improved construction.

In the accompanying drawings:-

Figure 1 shows a vertical section of a typewriting machine, only such parts thereof as are necessary to illustrate my invention being shown.

Figure 2 is a detail view, showing the position of a type bar when it has reached the momentum period, and this figure indicates how the type bars engage the universal bar

and how the connections between the type bars and the key levers are brought to a dead center or toggle-locking position when the keys are depressed. This figure of the drawings also indicates the position of the connections when the type bars are moved to the printing point.

Figure 3 shows a section on the line 3—3 of Fig. 1 and illustrates certain important parts of the universal bar mechanism.

Figure 4 is a detail view of parts of the universal bar.

Parts of a typewriter carriage are indicated at A and B indicates a platen; C shows a type bar segment and D a type bar guide; E indicates escapement mechanism. The type bars F are pivoted at f to the segment which, as usual, is semi-circular and is vertically arranged. Normally the type bars lie horizontally and are supported by a cushioned frame G. The key levers H are arranged in four banks or rows and are all of the same length. They are pivotally mounted in bearings h in an inclined frame I. The key levers are thus arranged in different horizontal planes. They move about four different axes corresponding with the positions of the finger-pieces of the levers. The front portions of the key levers extend through a frame J which acts as a dust-shed and the upward movement of the levers is limited by cushioned stops K.

Each key lever is formed intermediate its ends with an upwardly extending arm h'. Each arm is located the same distance from the pivot point of its lever. Each lever, it will be observed, is of the second order, inasmuch as the weight to be overcome is applied to the arm h', in the manner next to be described.

Each type bar F is directly connected with the arm h' of an appropriate key lever by a link L, said link being pivoted at z to the heel of the type bar below its pivot, and pivotally connected at y with the upper end of the arm h' of the associated key lever. Normally the key levers and the type bars lie horizontally, as shown in Fig. 1, but when a key is depressed the associated type bar is raised towards the platen, in the manner presently described. In order to return the type bars and the key levers to normal position I employ springs M, one for each type bar, and its associated lever. Each spring is attached to a type bar in front of its pivot

and to a lug m on a link L some distance from its connection with the type bar. These lugs m may be located the same distance from the type bar pivots so that springs of the same length may be employed which is a convenience in assembling the parts. When a key lever is depressed the associated type bar is raised to the position F' shown by dotted lines in Fig. 1. At this time the pivot 5 points x and y at opposite ends of the link L are in a straight line with the pivot f of the type bar. This is a dead center or toggle-locking position and tends to arrest the further movement of the type bar but the type 10 bar is carried to the printing point by its momentum. In this way the noise produced by the impact of the type bar on the platen is materially reduced. The position F' at the commencement of the momentum period 15 is preferably considerably more than 5° from the platen. The position of a type bar when it strikes the platen is indicated at F^2 .

By employing key levers of the second order, arranged in the manner shown, levers 20 of the same length may be used; they may all be depressed to the same extent and they exert a uniform pull on the type bars to move them to the platen. The direct connection of the key levers with the type bars 25 is an advantage inasmuch as it dispenses with other links or levers which are employed in some other constructions.

The escapement mechanism is in general of well known construction. As shown in 30 the drawings e indicates an escapement wheel; e' a fixed dog; e^2 a limber dog and e^3 a rocker plate pivotally mounted at e^4 . This escapement mechanism is operated by universal bar mechanism actuated by the type 35 bars.

The universal bar comprises a frame N having a semi-circular front part n adapted to be engaged by lugs f' on the heels of the type bars in rear of their pivots. The front part n of the frame is supported by 40 arms n' pivotally connected to the frame at n^2 and pivotally connected at their lower ends to a horizontally arranged rocker rod O , carried by the front end of arms P , rigidly connected with a rigidly supported bar Q . An arm R , mounted to turn on the frame bar Q , extends upwardly therefrom and is connected by a link S with the escapement rocker plate 45 e^3 . Said arm R is pivotally connected at r with a part of the frame N , as shown. A spring T , attached to the arm R intermediate its upper and lower ends, extends 50 rearwardly and downwardly therefrom to an arm U rigidly mounted on the frame bar Q . This spring tends to hold the universal bar mechanism in normal position and to return it to such position at the proper time.

When a key is depressed and a type bar is

actuated the lug f' on said type bar first engages the frame N , in the manner indicated in Fig. 2. When it thus comes into engagement with the frame, the type bar is in the position indicated at F' at the commencement of the momentum period. As 70 the type bar moves to the platen the frame N is moved forwardly, the arms n' swinging on their pivots n^2 in the manner indicated in Fig. 4. This figure of the drawings shows by dotted line the forward position of the parts and it will be observed that the mechanism is such that a parallel motion is obtained. By reference to Fig. 3 it will be observed that the arm R is held on the frame 75 bar Q between the hub of the arm U and a set collar u so that while the arm R is free to turn on the frame bar it is prevented from wobbling or from moving endwise thereon.

The mechanism is so constructed that the universal bar operates efficiently when the parts are either in upper or lower case position. The dotted line s in Fig. 1 shows the position of the link S when the carriage is 80 shifted for upper case printing. The frame N and many other parts of the universal bar mechanism may be made of sheet metal and being thus light can be easily operated.

I claim as my invention:

1. In a typewriting machine the combination of key levers of the second order having upwardly extending arms, type bars, links of different lengths connecting the type bars with the upwardly projecting arms of 100 the key levers, and springs of the same length connected with the type bars in front of their pivots and with the links behind the arms of the key levers.

2. In a typewriting machine the combination of type bars, key levers of the second order link-connected therewith, a dust-shed through which the key levers extend, and stops on the dust-shed for limiting the upward movement of the key levers.

3. In a typewriting machine, the combination with the key levers and the type bars, of escapement mechanism including a rocker plate, and universal bar mechanism comprising a frame moved forwardly by the type bars in their movement, a rocker rod which is arm connected to the frame, means for supporting said rod, a vertical arm pivotally mounted at its lower end and pivotally connected to the universal bar frame 115 at its upper end, and a link connection between said arm and the escapement rocker plate.

4. In a typewriting machine the combination with the type bars and the key levers, of escapement mechanism including a rocker plate, and universal bar mechanism comprising a curved frame, a supporting rod therefor, arms pivotally connected with said frame and with said rod, a frame bar, arms 125

extending forwardly from the frame bar and supporting said rod, an arm extending upwardly from said frame bar and pivotally connected with the universal bar frame, 5 a link connecting said arm with the escapement rocker plate, and a spring for holding the parts in normal position.

5. In a typewriting machine, the combination of the type bars and key levers of the 10 second order arranged at different levels, said levers having upwardly projecting arms of uniform length, and links of different lengths connecting the key levers with the type bars, the full depression of any key 15 lever moving the link to a dead center position with the type bar at a distance from the platen from which position it completes its

travel by momentum alone, thus reducing noise.

6. In a typewriting machine, the combination of the type bars and key levers of the second order having upwardly projecting arms, links of different lengths pivoted to the type bars and to the said arms, the full depression of any key lever moving the link 20 to a position in which its ends are in a straight line with the type bar pivot with the type bar at a distance from the platen from which position it completes its travel by momentum alone, thus reducing noise. 25

It testimony whereof, I have hereunto subscribed my name:

EDWARD B. HESS.
